UNITED STATES PATENT OFFICE.

LOUIS JENSEN, OF CHICAGO, ILLINOIS, ASSIGNOR TO UNITED AUTOGRAPHIC REGISTER COMPANY, OF CHICAGO, ILLINOIS, A CORPORATION OF ILLINOIS.

AUTOGRAPHIC-REGISTER CASH DRAWER.

Application filed March 25, 1926. Serial No. 97,297.

My present invention relates to a combined autographic register and cash drawer, and has particular reference to the means for releasing and unlocking the drawer during the discharge of a ticket or set of tickets from the register. The structure is so arranged that the drawer is released and opened once during the feeding of each ticket or set of tickets through the register, so that when each sale is made and the ticket or tickets are being delivered from the machine the drawer will be opened and the operator or clerk may have access to the interior of the drawer for depositing the cash received and for making change for the customer, as the case may be. In connection with the foregoing there is also provided simple means for re-winding and storing within the register the record strip or what is frequently termed the "summary strip", and the mechanism for stopping the re-wind of this summary strip prior to the complete discharge of the other tickets may be utilized to re-set the drawer latch or its releasing mechanism. Numerous objects are contemplated in the structure disclosed, among which are the provision of a combined autographic register and cash drawer that is compact in arrangement, dependable in operation, economical to manufacture, and novel in construction. All of the objects I prefer to accomplish in substantially the manner hereinafter fully described and as more particularly pointed out in the claims, reference being made to the accompanying drawings that form a part of this specification.

In the drawings:—

Figure 1 is a perspective showing the combined cash drawer and autographic register, the former being partially opened.

Figure 2 is a longitudinal vertical section taken on line 2—2 of Figure 4 and looking in the direction of the arrows, with the parts drawn approximately full-size and showing the latch releasing mechanism in its normally locked position in full lines and in its second position, but prior to releasing the latch, in broken lines.

Figure 3 is a view similar to Figure 2 showing the relative positions of the parts after the cash drawer has been released.

Figure 4 is a transverse vertical section taken on line 4—4 of Figure 2 looking in

the direction of the arrows, and drawn on a slightly reduced scale.

Figure 5 is a fragmentary detail of the mechanism for locking the drawer with a key so as to permit the autographic register to be used without opening the drawer.

Figure 6 is a longitudinal section through the lower feed device and restarter mechanism.

The accompanying drawings are more or less schematic for the purpose of illustrating the principles of my invention applied in a typical or preferred manner, and in said drawings similar reference characters have been employed to designate the same parts wherever they appear throughout the several views.

The structure preferably comprises a rectangular shaped base 10 that is short in height and hollow, and has its vertical end wall nearest to the operator omitted to permit the sliding drawer 11 to move back and forth. The drawer has the usual cash compartments or pockets, and upon its longitudinal side walls are angle-metal tracks or guide strips 12 that cooperate with a plurality of anti-friction rollers 13 mounted on the interior of the side walls of the base to permit of the easy movement of the drawer. For convenience, the drawer is adapted to be projected outwardly a certain distance in an automatic manner when it has been unlatched, and for this purpose I mount a spiral conical spring 14 upon the central portion of the wall of the base farthest from the operator, which spring will be compressed and under tension when the drawer is pushed inwardly and latched. A bracket 15 of substantially U-shape is secured to the wall of the base alongside the spring 14 and the parallel arms of the bracket extend away from the wall towards the rear of the drawer and afford bearings for a pivotal rod 16 that projects beyond said bearings to and into the longitudinal side wall of the base as seen in Figure 4, where it is specially formed as at 16^a to be engaged by a suitable key 17 that may be inserted by authorized persons through a key-hole in the side wall so that the rod 16 may be rotated to unlatch the drawer without releasing or operating the autographic register. The latch-bolt 18, having a lateral hook-shaped end 19, is secured upon the pivotal rod 16 between the

bearings of the latter by a set-screw 20, and a coiled spring 21 surrounds rod 16 with one end connected with the bracket 15 and its opposite end engaging the latch bolt 5 so as to urge the latter in a downward direction. The inner end wall of the drawer is provided with an upstanding member 22 in alignment with the latch-bolt so as to be engaged by the hooked end of the latter 10 when the drawer is in its innermost position to latch the same and maintain it against the tension of the ejector spring. Suitable means are provided upon the opposite longitudinal side-wall of the base for locking 15 the drawer and preventing its being opened whenever it is desired to operate the autographic register by itself. This structure comprises a tube 23 that is inserted in the wall and has a transverse partition 24 that 20 is apertured for the passage of a stud 25 projecting from the end of a cylindrical block 26 rotatably mounted in the tube upon the opposite or inner side of the partition. An eccentric or crank-pin 27 projects from the 25 inner end of the block 26 through a longitudinal slot 28 in an oscillating arm 29 pivotally mounted on the side wall of the base and which has a lateral upstanding lug 30 upon its movable end. This arm is so positioned that when the crank-pin is rotated 30 the lug 30 will enter a transverse recess or slot 31 in the lateral flange of the adjacent guide strip 12 on the drawer and thus prevent the longitudinal movement of the 35 drawer in either direction even though the latch bar 18 may have been released or raised.

The means for releasing the latch bolt 18 from the drawer is preferably controlled by 40 some portion of the mechanism that feeds the paper through the autographic register, and as will be seen in the drawings, the structure is "set" or rendered operative by the mechanism that controls the restarter or 45 the re-wind and slack in the summary or record strip and is released to unlatch the drawer by the mechanism that feeds out the other strips. It of course will be understood that other instrumentalities of an autographic register may readily be employed 50 for this purpose and that the disclosure herein is merely a typical or preferred manner of embodying the principles of my invention.

55 The casing 32 of the register is mounted upon the central longitudinal portion of the hollow base 10 and houses the rolls 33 from which the paper strips are unwound and led over the platen or writing bed 34 forming 60 the upper wall of the casing. The paper is moved by means of the opposing rotatable feed elements 35 and 36, the former being a roller and the latter being disks or flanges mounted upon a hollow shaft 37, the ends 65 of the shaft passing through and are jour-

naled in the side walls of the housing and rotated by an operating crank or handle 38 secured to one of the ends of the shaft 37. Gears 39 and 40 operatively connect shaft 37 with the spindle of the upper feed roller 70 so that the feed elements move in unison and when the perforation α in the paper strips come into registry with the disks or flanges 75 36 the feed of the paper is discontinued and the superposed strips will be brought into registration with each other. An idle gear 41 connects the lower feed with a pinion 42 on the adjacent end of a transverse shaft 43 extending across the casing and journaled in the side walls thereof and below the pinion 42 is an idle pinion 44 that is 80 adapted to be engaged and disengaged by a cam gear 45. The cam gear normally hangs pendent upon the pin 46 secured to and projecting from the adjacent end of one 85 of the arms of a rocking lever or bell-crank. This bell-crank comprises two arms 47 and 48 disposed oblique to each other, upon the former of which the cam gear is mounted eccentrically and said bell-crank is fulcrumed 90 at the juncture of its arms upon a pivot element 49 projecting from the side wall of the register casing. The outer end of the arm 48 of the bell-crank has pivotal connection with a link 50 that passes through the bottom and top respectively of the register casing and the hollow base. The lower end of the link 50 is provided with a longitudinally elongated slot 51 to receive the shank of a pin 52 or the like mounted on the adjacent 100 portion of the latch bar 18 back of the cash drawer. The normal position of the gears, bell-crank and the link, and latch-bar are illustrated in full lines in Figure 2 wherein it will be seen the pin 52 is in the lower end 105 portion of the slot 51 of the link so that the drawer may be unlocked by means of the key 17 which will lift the latch-bar 18 to disconnect its end from the upstanding member 22 on the drawer, such movement of the 110 latch bar being permitted by the slot 51 in the link.

In order to maintain the bell-crank and link structure in their normal positions I provide a trigger in the form of an arm 53 115 pivoted upon a screw 54 on the side wall of the register casing, the lower end of the arm being engaged in the notch 55 on the edge of the bell-crank arm 47 and in order to maintain these parts in the manner just 120 described I provide a coiled contraction spring 56 one end of which is connected to bell-crank arm 47 and the other end of which is connected to a projection 57 on the end of the trigger arm 53 nearest its pivot. Beyond 125 the pivot 54 the trigger has an oblique extension 58, the purpose of which will be presently described.

The summary or record strip, which is the 130 lowermost of the superposed strips that are

5 moved over the platen 34, passes from the feed member downwardly into the register instead of being discharged out of the end of the register with the other tickets and it
 10 is rewound upon a spool 59, the spindle 60 of which is mounted in the side walls of the register casing. The rewind of the summary strip is adapted to be stopped before a whole ticket has been discharged from the register in order that slack may be created in the summary strip to prevent pulling or binding of the same. This stoppage of the rewind spool is accomplished by providing a ratchet disk 61 upon the spool that is
 15 intermittently engaged by the serrations 62 upon the adjacent end of a pawl 63 that is pivoted on a pin 64 secured to the side wall of the casing and beyond its pivot the pawl is provided with a lateral extension 65 that
 20 projects upwardly alongside of and engages with the oblique extension 58 of the trigger. A coiled contraction spring 66 is connected at one end with the lateral extension 65 and at its opposite end is secured to a screw or
 25 the like 67 on the adjacent wall of the register casing so that the tendency of the spring is to urge the serrated end of the pawl 63 toward the ratchet disk on the rewind spool. A lateral pin 68 projects from the upper end
 30 of lateral extension 65 through a slot or opening in the register casing and it is engaged by a finger 69 projecting down from the depressible key element 70 that is mounted upon the outer extended end of a rock
 35 shaft 71 journaled in the side walls of the register casing. The opposite end of the rock-shaft 71 has a pawl 72 secured to it and said rock-shaft is maintained with the key in its normal upper position (Fig. 2)
 40 by means of a coiled spring 73 that surrounds the shaft and has its ends engaged respectively with the pawl 72 and the adjacent side wall of the casing. Thus when the control key 70 is depressed by the operator
 45 to the position shown in dotted lines in Figure 2 its finger 69 will, through its engagement with pin 68 on the lever extension 65 raise the serrated end of the pawl 63 to disengage the same from the ratchet disk 61
 50 and release the latter for rotation with the rewind spool. This movement of the lever extension 65 will move the trigger extension causing the lower end of the trigger arm 53 to move out of the notch 55 on the bell-crank
 55 arm 47, whereupon the spring 56 will pull said arm 47 upwardly bringing the normally pendent eccentrically mounted gear 45 into mesh with the lower pinion 44 of the gear train. At the same time the opposite arm
 60 48 of the bell-crank will have moved downwardly until the upper portion of the slot 51 in link 50 has engaged with the pin 52 but the link has not as yet moved the latch bar 18. The crank or handle 38 is now operated in the direction of the arrow (Fig. 2)

which operates the feed elements and causes the gear-train to move in the direction of the arrows in Fig. 3. As seen in Figure 2 the portion of eccentrically mounted gear 45 nearest its axis of rotation is the first portion 70 to be meshed with pinion 44 and be moved thereby and as said eccentric gear 45 rotates the axis of rotation is moved farther from the point of mesh with the pinion so that the bell-crank is rocked upon its pivot 49 thus moving the link 50 in an upward direction until the lower end of its slot 51 engages the pin 52 and thereafter the latch bar 18 is lifted to release the drawer and permit it to be projected outwardly by the 80 spring 14. The extreme position of movement of the eccentric gear, the bell-crank and the link are diagrammed in Fig. 3, which illustrates the latch bar lifted to its fullest extent. Continued operation of the crank or handle rotates the feed disks until the next succeeding perforations in the paper strips come into registry with said disks and further discharge of the strips is stopped,— 85 also the gear train will continue to rotate in the direction of the arrows until the contacting or meshing portion of eccentric gear 45 approaches the axis of rotation or to a point where the teeth of the eccentrically mounted gear 45 will disengage the teeth on pinion 44 when said gear will drop away from the pinion 44 and return to its normal or pendent position. The bell-crank begins to rock in the reverse direction after the eccentric gear passes what might be termed 90 “dead-center” or when its meshing portion is farthest from the pivot of the gear, which movement of the bell-crank will return the link 50 and latch bar 18 to their normal or initial position where the latch may be engaged with the co-acting element on the rear of the drawer whenever the drawer is pushed back into the hollow base by the operator. At about the time the gear 45 drops out of mesh with pinion 44 the pawl 63 will have 100 moved to stop the winding of the summary strip so that the extension 65 of the pawl will change from the dotted to the full line position shown in Figure 2. This permits the trigger to oscillate to its full line position and thus engage the bell-crank arm 47 to maintain the rocking element (bell-crank) against further movement during any further portion of the cycle of movement of the device. So long as gear 45 engages the 105 pinion 44 said gear will operate the rocking element or bell-crank and upon disengagement of the gear and pinion the gear will cease operating the rocking element. It may be here stated that when the key 70 is depressed to initially set the mechanism the lower end of the trigger arm 53 is moved out of the notch 55 in bell-crank arm 47 and will be in position over the next notch 74 in said arm which provides clearance for the 110 115 120 125 130

lower end of the trigger arm 53 when the bell-crank is operated. A curved or crescent-shaped spring 75 is secured to the base of the casing and extends upwardly along- 5 side of the gear 45 in order to prevent said gear swinging around too far on its pivot 46 when it has been released from mesh with pinion 44.

As before stated, when the key 70 is de- 10 pressed the serrated end of the pawl 63 is dis- engaged from the ratchet disk 61 of the re- wind spool;—at the same time, the restarter mechanism is rendered operative. The re- starter operates upon the principle disclosed 15 in the pending application for Letters Patent in the names Walter R. Barker and myself which was filed February 9th, 1922, Serial No. 535,293, and the mechanism for co-ordinating the re-starter with the rewind spool 20 for the purpose of providing slack in the summary or record strip is disclosed in the pending application for Letters Patent in the names of myself and Charles Winter which was filed January 25, 1923, Serial No. 25 83,634. Disposed in the interior of the in- terior of the hollow feed shaft 37 is a solid shaft 75 that is adapted to rotate with the hollow shaft and is also capable of independent longitudinal movement within the shaft. 30 This solid inner shaft 75 is connected by transverse pin 76 with a cam element, in the form of a hollow sleeve 77 having external threads 78 that are engaged by the pawl 72, said pin passing through the solid inner 35 shaft 75 and through longitudinally elongated slots 79 in the outer tubular shaft in which slots the pin may move longitudinally of the shaft. The inner solid shaft 75 is urged in one direction by a coiled ex- 40 pansion spring 80 seated between the inner end of solid shaft 75 and the inner end of the tubular portion of hollow shaft 37. When the key 70 is depressed shaft 71 is rocked and raises the pawl 72, which is normally en- 45 gaged with the end edge of the cam element 77 as shown in Figure 4 thus permitting the cam element to be projected under the pawl so that when the latter is lowered it will engage with the threads 78 of the cam ele- 50 ment. The rotation of the feed roller shaft 37 by the operating crank will rotate the cam element on the end of shaft 37, which by its engagement with the pawl 72 will be moved back towards its normal position until 55 the pawl element reaches the end of the threads where it moves off the end of the cam element into engagement with the adjacent end of the shaft, which will cause the rocking of the shaft 71 back to its normal 60 position thus raising the key 70 and permit the serrated end of pawl 63 to engage the edge of the serrated disks 61 of the rewind spool and stop further rotation of the latter. This takes place prior to the time the per- 65 foration X in the paper strips reach the feed

disks or flanges 36 so that all of the strips, including the record or summary strip are moved forward the remaining distance to the perforations which creates the desired slack in the summary or record strip. The 70 summary spool is rotated by a train of gear that is actuated by a portion of the gear train heretofore described and consists of a pinion 81 on the outer end of the rotatable rod 43 that meshes with the gear 82 forming one 75 of a pair of frictionally connected gears mounted upon the exterior of the casing. Gear 82 is spaced from and driven with its companion gear 83 by means of friction disks 84 that are interposed between them. A pin- 80 ion 85 (Fig. 3) is mounted upon the outer end of the spindle 60 of the summary spool in mesh with and driven by the gear 83 so that the summary spool is rotated by the feed devices through the gear trains. 85

The restarter mechanism comprises an annulus 86 normally loose upon the shaft 37 alongside a fixed collar 87 secured to said shaft and said annulus has a tapered bore 88 of greater diameter than shaft 37 that per- 90 mits the annulus to hang eccentric on the shaft when not in operative position, and when the annulus is centered on the shaft by the cone-shaped clutch element 89 on shaft 37 the periphery of the annulus will be placed in coactive relation with the central portion of the upper feed roller 35 inter- 95 mediate the longitudinal rows of perfora- tions, so that by rotating shaft 37 the paper strips are initially moved by the annulus a distance sufficient to carry the perforations 41 out of registration with the feed disks or flanges 36. The cone clutch element 89 is mounted upon the tubular shaft 37 by a pin 90 that passes through longitudinally elongated slots in said shaft and through a trans- 100 verse slot 92 in the solid shaft 75 (Fig. 6) A coiled spring 93 surrounds the shaft 37 between the base of the cone 89 and the hub of the adjacent disk or flange 36 so as to urge 105 the cone towards the annulus. When the pawl 72 has been raised from the end edge of the cam sleeve 77 the inner solid shaft 75 will be moved towards the right, Figs. 4 and 6, thus permitting the cone to center 110 the annulus. While the cam sleeve 77 is moving to the left during the feeding operation the inner shaft 75 is correspondingly moved until the end of the slot 92 therein 115 engages the pin 90 thereby moving the cone away from the annulus to release the latter and permit it to again assume an eccentric 120 position and disengaged from the roller 35 and the paper strips. 125

The mechanism hereinbefore described is so arranged that upon the depression of the key 70 the drawer latch will be set or placed in an operative position to be released during the feeding out of the tickets on the paper strips and the respective operations are syn- 130

chronized so that a set of tickets must be partly discharged before the drawer 11 is unlocked and released. The setting of the latch takes place simultaneously with the 5 centering of the restarter annulus 86 to initially feed the paper strips and the time of release of the drawer is determined by the relation between the eccentrically mounted gear 45 with the pinion 44, as well as the 10 construction and arrangement of the link 50 and the bell-crank upon which said eccentric gear is mounted. While the mechanism herein disclosed is desirable and convenient it is not, however, necessary, as another 15 autographic register means may be utilized for the purposes specified, the disclosed mechanism being a typical embodiment of the principles involved.

What I claim is:

20 1. A device of the kind described comprising a hollow base, a drawer movable therein, a latch for maintaining the drawer normally closed, a rocking device for operating the latch, a gear train and actuating means 25 therefor, and an eccentrically mounted element operated by the gear train whereby to actuate said rocking device and release the latch, said element adapted to gravitate out of cooperative relation with the gear 30 train to cease operating the rocking device.

2. A device of the kind described comprising a hollow base, a drawer reciprocable therein, a latch for maintaining the drawer normally closed, a rocking device for controlling said latch, an eccentrically mounted element having operative connection with said rocking device, and means for actuating said eccentrically mounted element, said element adapted to gravitate out of cooperative 35 relation with said actuating means to cease operating the rocking device.

3. A device of the kind described comprising a hollow base, a drawer reciprocable therein, a latch for maintaining said drawer normally closed, a rocking lever operatively connected to said latch, an eccentric element mounted upon and carried by one end of said lever, and means for actuating said eccentric element, said element adapted to gravitate 45 out of cooperative relation with said actuating means to cease operating the rocking lever.

4. A device of the kind described comprising a hollow base, a drawer, reciprocable therein, a latch for maintaining said drawer, normally closed, a gear rotatable upon an eccentric axis, a gear train for actuating said gear, and means operatively connecting said first-named gear with said latch.

5. A device of the kind described comprising a hollow base, a drawer reciprocable therein, a latch for maintaining said drawer normally closed, a rocking lever operatively connected to said latch, a gear rotatable 50 upon an eccentric axis and mounted upon

one end of said lever, and a gear train operatively connected to said gear.

6. A device of the kind described comprising a hollow base, a drawer reciprocable therein, a latch for maintaining said drawer normally closed, a rocking lever fulcrumed intermediate its ends and one arm of which has operative connection with said latch, a gear rotatable upon an eccentric axis and mounted upon an arm of said lever, and 70 a gear train operatively connected to said gear.

7. A device of the kind described comprising a hollow base, a drawer reciprocable therein, a latch for maintaining said drawer normally closed, a bell-crank lever fulcrumed at the juncture of its arms, a link operatively connecting an arm of the bell-crank lever to said latch, a gear rotatable upon an eccentric axis and mounted upon 80 the other arm of the bell-crank lever, and a gear train operatively connected to said gear.

8. A device of the kind described comprising a hollow base, a drawer reciprocable therein, a latch for maintaining said drawer normally closed, a rocking lever operatively connected to said latch, a trigger normally maintaining said lever in an inoperative position, means for tripping said trigger to 90 permit said lever to assume an operative position, an eccentrically mounted operating element having operative connection with said lever, and actuating means adapted to be operatively connected to said eccentric element when said lever is in its 95 operative position.

9. A device of the kind described comprising a hollow base, a drawer reciprocable therein, a latch for maintaining said drawer normally closed, an eccentrically mounted element, means for rotating said element, said element being normally disconnected from said means, devices operatively connecting said element with said latch, and 100 means for moving said element into and out of operative relation with respect to its rotating means.

10. A device of the kind described comprising a hollow base, a drawer reciprocable therein, a latch for maintaining said drawer closed, an eccentrically mounted rotatable element, actuating means for said element, means operatively connecting said eccentric element with said latch, a trigger normally 110 maintaining said eccentric element disconnected from said actuating means, and means for tripping said trigger whereby said eccentric element assumes operative relation with its actuating means.

11. A device of the kind described comprising a housing, a rotatable shaft journaled in the walls thereof, a drawer reciprocable in said housing, a rotatable spindle, gearing including frictionally connected elements for 120 125 130

actuating said spindle from said shaft, devices for stopping the rotation of said spindle independent of said gearing, a key for releasing said devices to permit the rotation of said spindle, a latch normally maintaining said drawer closed, normally inoperative means operated by the shaft for releasing said latch, and a structure for normally maintaining said releasing means in an inoperative position and adapted to be operated by the movement of said key to render said releasing means operative to release the latch.

12. A device of the kind described comprising a housing, a rotatable shaft, a drawer reciprocable in said housing, a latch for maintaining said drawer normally closed, means operated by said shaft for releasing said latch, a spindle intermittently rotated by said shaft, mechanism for controlling the rotation of said spindle and normally maintaining said latch releasing means in inoperative position, and a device for moving said trigger whereby to permit the operation of said latch releasing means to release said spindle.

13. A device of the kind described comprising a housing, a rotatable shaft, a drawer reciprocable in said housing, a latch for maintaining said drawer normally closed, a rotatable spindle within said casing, a gear train operatively connecting said spindle and shaft, a rocking device adapted to release said latch, a gear train adapted to connect and operate said rocking device with said shaft one of said gears being normally out of mesh, a trigger for maintaining said last named gear in its normal position, pawl and ratchet devices for controlling the rotation of said spindle and means common to said pawl and ratchet devices and said trigger for rendering the same operative.

14. A device of the kind described comprising a housing, a drawer slidable therein, and means for controlling the movement of the drawer including an operating key, a latch for normally maintaining the drawer

closed, normally ineffective devices adapted to be intermittently operated to release the latch and said devices including a train of gear one of which is gravity controlled and moves away from the adjacent gear to discontinue operation of the latch, and other devices actuated by said key for rendering said latch devices effective.

15. A device of the kind described comprising a housing, a drawer slidable therein, and means controlling the movement of the drawer including an operating key, a latch for normally maintaining the drawer closed, devices adapted to be intermittently operated to release the latch and including a train of gear one of which is gravity controlled and moves away from the adjacent gear to discontinue operation of the latch, and a trigger operated by said key and adapted to normally maintain a portion of said release devices in non-operative position and when operated by the key to cause the same to assume its operative position.

16. A device of the kind described comprising a housing, a drawer slidable therein, and means controlling the movement of the drawer including an operative key, a latch for normally maintaining the drawer closed, devices adapted to be intermittently operated to release the latch and including a train of gear one of which is gravity controlled and moves away from the adjacent gear to discontinue operation of the latch, said devices also including a rock lever having operative connection with the latch, and a trigger which maintains said rock lever in an inoperative relation to the other portion of said release devices, said trigger having operative connection with said key whereby said trigger is adapted to be moved to free the rock lever and form operative connection with the remaining portion of the release devices.

Signed at Chicago, in the county of Cook, and State of Illinois, this 19 day of March, 1926.

LOUIS JENSEN.
